UNITED STATES PATENT OFFICE

RICHARD RUEMELIN, OF MILWAUKEE, WISCONSIN

AIR DRIER

Application filed November 8, 1929. Serial No. 405,764.

My invention relates to an air drier adapted to be used in connection with compressed air to provide a means of drying and cooling the compressed air or removal of oil vapors in the air. The drier may be placed in the pipe line of the air so as to remove the objectionable moisture in the same.

A feature of my invention resides in an air drier of a compact nature having a simple structure which is adapted to operate automatically to remove the objectionable moisture and oil from the air and to cool it so that when the compressed air is used in conjunction with paint spraying, sand blast equipment, or other equipment, such as die casting and pneumatic tools, the compressed air is furnished from my drier with the surplus moisture removed therefrom. Compressed air from my drier may be mixed with sand for sand blasting without danger of clogging the air and sand line. My drier is also very efficient with paint spraying because water or oil destroys the coating and in die casting water in the compressed air line forms dangerous pressure, whereas, in pneumatic tools water cuts the lubricant and wears out the tools. All of these disadvantages in the ordinary use of compressed air are overcome by my drier.

In using compressed air with sand for sand blasting, it is desirable to maintain the air with a minimum moisture content and to remove the excess moisture before the air comes in contact with the sand or the mixing equipment. My air drier is inexpensive, operates automatically and does not retard the operation of the compressed air but removes the moisture to form an automatic drier and also lowers the temperature of the compressed air in a very efficient and desirable manner.

It is a feature of my invention to provide an air drier having means of collecting the moisture as the air passes through the same so that the operation is automatic and to provide either water or air cooling means to the drier so that the excess moisture content may be removed from the air entirely automatically in the use of my drier. My drier is of a compact construction, having no moving

parts and may be designed with various shaped internal baffles about which the air passes so as to collect and drain the moisture content in the air by a combined cooling and whirlpool action as the air automatically passes through the drier. Further, I provide a trap means in conjunction with my drier which drains away the moisture as it is collected and operates automatically to discharge the moisture and keep the drier empty of excess moisture which it may collect in its operation.

A feature resides in a drier made principally of two parts which are connected together to form the drier in its entirety and wherein the part of one portion may interfit into the part of the other portion of the drier, so that when the two parts are connected together they form the complete drier, all of which parts are compact and operate to dry and cool the compressed air which passes through the same.

A feature of my drier resides in means for cooling the same by a refrigerating medium such as a refrigerating coil operable either by an electrically operated refrigerating means or any other refrigerating means adapted to direct controlled refrigerant directly about the air passageways for the compressed air of the drier.

These features together with other details, particular formation and arrangement of the parts of my automatic air drier for compressed air lines will be more fully and clearly set forth throughout the specification and claims.

In the drawings:

Figure 1 illustrates a side view of my drier as it would appear in use with the drain trap in cross section.

Figure 2 is a section through my drier in the type where water is employed to cool the same.

Figure 3 is a view on the line 3—3 of Figure 2, looking toward one half of the drier with the parts in full lines.

Figure 4 is a section of another form of my drier, where the outer atmosphere is used for cooling.

Figure 5 is a section on the line 5—5 of

Figure 4, showing one half of the drier, each half being virtually the same.

Figure 6 is a vertical section of a form of my drier similar in function to that illustrated in Figure 2, but having the inner parts thereof of a slightly different formation.

Figure 7 is a section on the line 7—7 of Figure 6.

Figure 8 is a side sectional elevation of a 10 form of my drier.

Figure 9 is a section on the line 9—9 of Figure 8.

Figure 10 illustrates another vertical section of my drier.

15 Figure 11 is a section on the line 11—11 of Figure 10.

Figure 12 is a vertical section of a form of my drier.

16 Figure 13 is a section on the line 13—13 of 20 Figure 12.

My drier A is primarily designed of a simple nature adapted to be used in air lines where compressed air is used for sand blasting purposes and the like, and where it is 25 important that the compressed air have a uniformly dry nature irrespective of the outer atmosphere. In sand blasting the compressed air is mixed with the sand and under varying atmospheric conditions the moisture

30 in the air is often detrimental to the operation of the sand blasting equipment. By my drier A I provide a means of automatically drying the air as it is used and the drier A is formed of two main parts 10 and 11 which

35 constitute the sides of the drier. The parts 10 and 11 are adapted to be bolted together centrally by the flanges 12 which are formed on the parts 10 and 11 and which may be clamped together by suitable bolts 13 which

40 extend through the flanges. A gasket positioned between the flanges 12 provides a tight joint so that the members 10 and 11 are connected together to form a single unit providing a compact air drier A of a very desirable

45 nature for permitting inspection or cleaning. The parts 10 and 11 of the air drier A are more clearly exemplified in the section in Figure 2 and the side view in Figure 3. Each of the parts 10 and 11 are virtually of the

50 same general nature excepting for minor details which will be hereinafter more clearly pointed out. The part 10 is provided with an air inlet opening 15 which may receive the air inlet pipe 16. This inlet is at the top of

55 the drier A so that the air is passed into the drier A at the top. The portion 11 is formed with an air outlet opening 17 and by means of the pipe 18 the air may be exhausted out of the drier A.

60 My air drier A may be cooled by means of the chambers 8 formed in each of the parts 10 and 11 and which may be connected with a water or refrigerating line by means of the pipes 19 and 20 so that the water may circ-

The internal formation of my air drier A is such as to provide a series of inwardly projecting baffles B, and each part 10 and 11 is formed with these similarly shaped baffles B, the outer end of the head portions 21 of the baffles B being formed to project beyond the clamping surface of the flanges 12. The head portions 21 in the form of my drier A in Figures 1 and 2 and also in Figures 6 and 7 70 may be formed enlarged to provide corner channels or ridges 22 against which the air entering through the opening 15 is adapted to strike in passing through the drier A.

It is desirable to place the baffles B with their outer ends projecting toward the adjacent portion 10 and 11 and in the form of the construction of my drier A in Figures 2 and 3 I provide an inner zigzag wall formation, such as 24, which carries on the apex of the inside of the zigzags of the walls 24 the baffle 80 members B with the retarding heads 21. This forms a zigzag air passageway 25 from the upper chamber 26 which receives air from the inlet 15 and carries it to the lower chamber 27 where it is exhausted out through the opening 17.

In the lower chamber 27 I provide a drain opening 28 which is connected by the drain pipe 29 to the drain trap 30. Within the drain trap 30 I provide an automatically operated float valve C which is operated by the collection of moisture in the same so that when an excess amount of moisture is collected therein, it may be discharged out through the discharge opening 31.

Thus in the operation of my air drier A the drier A is placed in the line of the compressed air leading from the compressor and reservoir for holding the compressed air to the line of use, the pipes 16 and 18 representing the inlet and outlet passageways or airline from the compressor and reservoir. Then as the air is used for sand blasting as it passes

from the compressor and reservoir through the air drier A it is cooled and dried and carried for use to the sand blasting equipment in a virtually uniform condition, that is, as to the moisture or oil content. The construction of my air drier A may be as large or as small as desirable for the particular use to which it may be placed and as the air passes in the inlet opening 15 it will be directed through the passageway 25 coming in contact with the baffles B and the channels 22. As the air passes through the drier the moisture in the same will collect in the channels 22 and run on down to the drain opening 28 into the trap 30. The air will also be cooled in my drier before it passes out

115 120 125 130 through the exhaust opening 17 which aids in condensing the moisture therein and automatically collecting the moisture out of the air by my drier A. There are no moving parts in my drier and its operation is simple and effective so as to collect the undesirable 130

65 circulate through the water chambers 8.

moisture in the compressed air before it comes in contact with the sand and sand blasting equipment. This is very important in the successful operation of sand blasting devices and I have found my drier to operate most effectively.

In Figures 4 and 5 I have illustrated my air drier A designed with cooling flanges D which are formed to project from the walls 10 24 of the same and which operate to cool the air passing through the drier A, taking the place of the water cooling means. This form of my air drier also operates effectively in certain uses and sufficiently cools the air passing 15 through the same at the same time that the air is freed from its surplus moisture.

In Figures 6 to 13, inclusive, my air drier A is of the same general construction, having the same function for the relatively co-operating parts. The air is inhaled into the passageway 15 and exhausted out of the passageway 17 of each of these forms of my drier A. In Figures 6 and 7 the baffles B are formed similarly to those in Figure 2, however, the 25 side walls 24 have a somewhat different shape in that they are arcuated around the ends of the baffles B rather than extending angularly to provide a zigzag air passage such as 25. In Figures 8 and 9 the portions 10 and 11 are 30 provided with inwardly projecting tubular portions 35 which are illustrated in cross section in the respective views and these tubular portions project in between each other when the two portions 10 and 11 are clamped together. Each of these protruding tubular 35 portions are hollowed to receive the water or refrigerant from the cooling chambers 8 on each side and are formed with channel 40 grooves 22 which collect the moisture as the air passes around the protruding portions 35. In the structure of Figures 10 and 11 the protruding portions 36 from each of the portions 10 and 11 are in the form of long vertically disposed members with vertical 45 water or cooling slots 37 extending into the same from the chambers 8. The protruding members 36 intermesh from the parts 10 and 11 and are formed with moisture collecting 50 grooves 38 between upwardly projecting transverse flange members 39 projecting from the sides of the members 36. These members 39 provide a zigzag air passageway for the compressed air over the protruding members 36.

In Figures 12 and 13 I have illustrated a form of air drier A wherein the portions 10 and 11 carry tubular inwardly projecting portions 40 which interfit when the portions 60 10 and 11 are connected together. These portions 40 are formed with a series of star-like points in the form of ribs 41 extending along the hollow portions 40. The hollow portions in the tubular portions 40 connect with the 65 water cooling compartments 19 and are closed

on the outer end in the same manner as the tubular portions 35 in the construction in Figures 8 and 9. The ribs 41 act to collect the moisture as the air passes over the portions 40 through the drier A in this form, and thus the moisture is collected into the bottom chamber of the drier and carried out through the trap 30. My drier A operates to automatically remove the excess moisture from the compressed air as the same passes through the line of travel from the compressor and before the air is mixed with the sand in sand blasting equipment. The simple structure set forth is such as to provide a drier which will not get out of order and which will thoroughly dry out the air to the extent desired, also removing oil vapors. Each of the structures of driers illustrated have the same general function and the flow of the air from the top to the bottom carries the moisture down to the bottom portion of the drier where it is drained out automatically. The obstructing ribs or ridges in the inner walls of the respective parts 10 and 11 act to collect the moisture and condense it as the air is cooled in passing through the drier.

While the drawings illustrate various formations of my drier the function of each is identical to accomplish the same result automatically as the air passes through the drier. While my drier may be particularly adapted to compressed air used in connection with sand blasting equipment it is equally applicable to the drying of air for any desirable purpose where it is important that the air be cleared of an undesirable amount of moisture and therefor my drier is applicable to various uses and may be applied wherever preferred owing to its simple nature where the same results are desired. Obvious changes may be made and other uses applied to the same than those above set forth without departing from the purpose and intent of the invention within the scope of the following claims:

I claim:

1. An air drier including, a pair of members secured together, and a series of interrupting baffles and horizontal moisture conducting grooves carried by said members forming an air passage through said drier to carry compressed air from an inlet at the top to an outlet at the bottom whereby the major part of the moisture is collected out of the air passing through said drier.

2. An air drier for compressed air including a pair of members secured together, an air inlet in the top thereof, an air outlet in the bottom, air interrupting shoulders on said members positioned within an air passage through said drier adapted to collect the moisture out of the air, and means for automatically draining the moisture collected by the drier out of the same.

3. A drier for compressed air including,

a casing, an inlet passageway and an outlet passageway in said casing, a zigzag passageway formed by baffles on said casing to connect with said inlet and outlet passageways, 5 cooling means about said passageway, and moisture collecting grooves positioned in each of said passageways.

4. An air drier including a pair of members secured together, an inlet passageway 10 and an outlet passageway in said members, a series of protuberances formed on said members in said drier, and a passageway leading over said protuberances to carry the air from the inlet to the outlet over the 15 protuberances, whereby the protuberances are adapted to pick up and separate moisture from the air automatically as the air passes through said drier.

5. An air drier including, a pair of similar members adapted to be bolted together, 20 an air passageway formed in said drier when said members are bolted together by spacing the inner walls of said members apart to form an irregular air passageway, and a series of 25 irregular protuberances projecting into said passageway acting as interrupters to automatically collect the moisture out of the air passing through said drier.

6. An air drier including, a pair of members 30 connected together, each of said members forming a substantial half of said drier, the inner sides thereof forming irregular air passageways in said drier, inlet and outlet passageways connecting with said irregular 35 passageways, a multiplicity of protuberances positioned in said irregular passageways, and an automatic drain trap connected with said air passageways to collect and drain out the moisture collected by said drier 40 from air passing therethrough.

7. An air drier including, a pair of similar members each having similarly shaped inner walls to form irregular air passageways therethrough when said members are 45 connected together, water cooling compartments in each of said members, inlet and outlet air passageways connecting with said irregular passageways, and a drain trap connected in the lower portion of said drier to 50 automatically drain moisture out of said drier which is collected from air passing therethrough.

8. An air drier comprising, members secured together, hollow protuberances formed 55 in each of said members having inner closed ends, said protuberances projecting toward each other from each of said members and in staggered relation to each other, water cooling compartments connecting with said 60 protuberances to cool the same, and inlet and outlet air passageways to direct air over said protuberances which automatically collect the moisture out of the air as it passes through said drier.

65 9. An air drier adapted to automatically

collect moisture from the air as it passes through the same including a series of members connected together, protuberances projecting from each of said members arranged in staggered relation to each other, and means for cooling said protuberances whereby when air passes over the same it is cooled and the moisture is collected therefrom to automatically dry the air as it passes through said drier.

10. An automatic air drier including, a series of members connected together, an inlet passageway and an outlet passageway, the inner sides of said members forming a series of irregular air chambers in said drier and connected with said inlet and outlet passageways, whereby air is automatically dried as it passes through said chambers from the inlet to the outlet of said drier.

11. An air drier including, a series of air baffle members forming irregular passageways, enlarged ends formed on said baffles, moisture grooves formed by said enlarged ends, and an inlet passageway and an outlet passageway connecting with said irregular air passageways.

12. An air drier comprising, a casing, a series of baffles forming irregular air passageways, ends formed on said baffles adapted to provide moisture collecting grooves, an air inlet at the top of said drier connected with said irregular passageways, and an air outlet connected with said irregular passageways at the bottom whereby air passing through said drier is adapted to be automatically relieved of the greater portion of its moisture content.

13. An air drier and vapor remover for compressed air including, a casing, a series of zigzag passageways formed in said casing adapted to interrupt the direct passage of air, shoulders causing a whirling action of the air as it automatically passes through said drier, means for cooling said passageways, and inlet and outlet openings for compressed air.

14. An air drier and vapor remover having, a casing, a series of baffles forming passageways through said casing a series of interrupting shoulders formed on said baffles, inlet and outlet passageways for compressed air, and refrigerating means for cooling said passageways, whereby compressed air passing through said drier is caused to be cooled and simultaneously interrupted to remove moisture, vapor and oil film therefrom.

15. An air drier including, a casing, a series of baffles in said casing forming passageways therethrough, a series of protuberances on said baffles causing whirling of the air through said passageways, refrigerating means for cooling said protuberances, inlet and outlet passageways connecting said irregular passageways, whereby compressed

air is automatically cooled and dried as it passes through said drier.

16. A rigid type air drier including, a casing, two members secured together to form 5 said casing, a series of protuberances on the inner walls of each of said members, said protuberances of each of said members inter-projecting with the protuberances of the other members, an inlet passageway at the 10 top of said casing, an outlet passageway at the bottom of said casing, and a passage between said interprojecting protuberances and said inner walls, said protuberances and inner walls acting to cool and dry air passing 15 therebetween.

17. An air drier for compressed air including, a casing comprised of two similar members secured together, an inner wall on each of said members, said inner walls spaced 20 apart to provide a passage therebetween, a series of protuberances on each of said inner walls extending into said passageway, means for cooling said protuberances, an inlet passageway and an outlet passageway in said 25 casing communicating with said passageway between said inner walls, whereby air may be passed through said casing and cooled by said protuberances.
